Primary Examiner—Ralf Seifert
Attorney, Agent, or Firm—Tilton Fallon Lungmus**[57] CLAIM**

The ornamental design for an identification bracelet, substantially as shown and described.

DESCRIPTION

FIG. 1 is a plan view of one side of the identification bracelet;

FIG. 2 is a plan view of the opposite side of the identification bracelet; and,

FIG. 3 is a perspective view of the identification bracelet. The broken lines in that figure represent environment structure and do not constitute any part of the design.
